UNITED STATES PATENT OFFICE

2,170,554

NEEDLE-LUBRICATING MECHANISM

Harold Ernest Elliott, Leicester, England, assignor to United Shoe Machinery Corporation, Paterson, N. J., a corporation of New Jersey

Application November 16, 1937, Serial No. 174,786
In Great Britain December 14, 1936

7 Claims. (Cl. 112—43)

The present invention relates to sewing machines, and more particularly to methods of and mechanism for lubricating the needle of sewing machines which are employed for sewing outsoles

5 to boots and shoes. Examples of machines for this purpose are illustrated and described in the patent to Ashworth No. 1,169,909, dated February 1, 1916, and in the patent to Gouldbourn et al., No. 2,056,670, dated October 6, 1936.

10 It has been found desirable in machines of the type described in the aforesaid patents, particularly in the case of machines which are operated at comparatively high speeds, to insure that the needle, after its withdrawal from the work upon

15 stopping the machine and before the machine comes to rest, is thoroughly lubricated in order to prevent sticky particles of tanning, leather, and the like from adhering to the hot needle and drying thereon, with the result that the needle is

20 frequently broken when the machine is again started due to the needle sticking in the needle guide.

It is, therefore, one of the several objects of the present invention to provide a method of and 25 mechanism for lubricating the needle of a sewing machine which will effectively lubricate the needle upon stopping the machine, whereby the breakage of needles upon starting the machine due to sticking of the needle in the needle guide

30 may be entirely prevented or at least reduced to a substantial degree.

Another object of the invention is to provide a 35 needle lubricating system in which the lubricant is forcibly applied directly to the needle without the intervention of a brush, pad, or other similar transfer device.

With these and other objects in view, a feature of the present invention consists in the method 40 of lubricating the needle of sewing machines, and in the provision in such machines of mechanism for lubricating the needle thereof, wherein lubricant is squirted or forcibly projected directly onto the needle itself, as distinguished from application by means of a brush or by being dropped onto a pad carried by the needle guide.

More specifically, a feature of the present invention consists in the method of, and in the provision in a sewing machine of mechanism for, lubricating the needle whereby lubricant is 45 squirted onto the needle, and if desired, also onto the needle guide, just at or slightly before the machine comes to rest at a time in the last cycle of the machine when the needle has withdrawn from the work and will not enter it again until 50 the machine has started, with the result that the

needle remains thoroughly coated with oil during the time the machine is at rest, thus enabling the needle to cool without particles of material drying thereon and firmly adhering thereto.

Another feature of the invention consists in the provision of a method and mechanism for lubricating the needle of sewing machines upon stopping the machine and subsequent to the withdrawal of the needle from the work, wherein in the time in the last cycle of the machine at 5 which the lubricant is squirted onto the needle may be varied, in order that the lubricant may be applied to the desired portion of the needle lengthwise thereof.

Other features of the invention consists in certain constructions and arrangements of parts whereby the amount of lubricant squirted onto the needle when the machine is stopped may be readily adjusted, and whereby the lubricant is squirted onto the needle only upon stopping the 20 machine and not when the treadle or other controlling means is actuated merely to reduce the speed of the machine.

The several features of the present invention will become apparent from the following description of a specific embodiment of the invention taken with reference to the accompanying drawings. The said embodiment will for convenience be described as being embodied in a sewing machine of the particular construction 30 disclosed in the aforesaid U. S. patent to Gouldbourn et al. No. 2,056,670.

In the drawing Figure 1 is a view in left hand side elevation of the illustrative embodiment of the invention, part of the head of a sewing machine to which it is fitted being shown in broken line; Figure 2 is a rear view of certain parts shown in Figure 1; and Figure 3 is a detail sectional view showing a portion of the needle, needle guide, and discharge end of the lubricating fluid conduit.

The said illustrative embodiment includes a bracket 1 secured to the rear of the machine head near the left hand side. The bracket 1 has secured to it a lubricant supplying pump 3, from which lubricant is conveyed through a pipe 5 to the vicinity of the needle 16, the pump 3 being similar to that shown and described in U. S. patent to Harold E. Elliott No. 2,051,250 dated August 18, 1936. The lubricant supplying pump 3 in the illustrative embodiment is positioned on the machine at the left hand side of the head of the machine at a higher level than, and a little forwardly of, the rocking shaft 6 referred to as 677 in aforesaid U. S. Patent No. 2,056,670. 55

The bracket 1 has pivoted to it on a horizontal pin 7 extending laterally of the machine a forwardly extending pump actuating arm 9, the forward end of which has adjustably secured in it a screw 11, the lower end of which is positioned above the plunger 12 of the pump and is arranged on downward movement of the arm 9 to depress the plunger 12 and cause lubricant in a reservoir of the pump to be forced along the pipe 5 and to be discharged therefrom. The pump actuating arm 9 has secured to its upper face about mid-way between its pivot 7 and its forward end a plate 13 the rear margin of which extends part way over an opening 14 passing upwardly through the arm 9 at the rear of the plate 13. Passing upwardly through the opening 14 in the arm 9 is the upper end of a bar 15 which near its upper end has formed on its forward side a shoulder 17 on which the rear margin of the plate 13 is supported when, as will hereinafter appear, the arm 9 has been moved to a raised position, to hold the arm 9 in its raised position. The bar 15 extends downwardly from its upper end at the rear of the rocking shaft 6 of the machine and at its lower end is pivoted to a bracket 19 secured on the head of the machine by a horizontal pin 21 extending laterally of the machine. The pin 21 is positioned in the machine rearwardly of and lower than the rocking shaft 6 and the front face of the bar 15 lies comparatively close to the rocking shaft.

The pump actuating arm 9 has connected to it the upper end of a downwardly extending rod 23. The upper end of the rod has formed in it a slot 25 through which passes a pin 27 secured in the arm 9. The lower end of the rod 23 is pivotally connected to an arm 29 of the clutch controlling mechanism of the machine similar to the arm referred to as 653 in the aforesaid U. S. Patent No. 2,056,670 which in that specification is described as being connected to the clutch controlling treadle of the machine and is swung upwardly when the forward end of the treadle is depressed to cause the machine to operate. The arm 29 to which the lower end of the rod 23 is connected has extending from its hub towards the right hand side of the machine an arm 31 to which the lower end of a tension spring 33 is connected. The upper end of the tension spring 33 is connected to the pump actuating arm 9. A member 35 secured on the rocking shaft 6 (for convenience a member similar to the block referred to as 675 in U. S. Patent No. 2,056,670) carries a roll 37 which is rotatably mounted on an eccentric portion of a pin 39 secured in the member 35 but rotatable therein. The roll 37 is so positioned on the member that it is engaged by the forward face of the bar 15 which passes through the opening 14 in the pump actuating arm 9 against which roll 37 the bar 15 is held by a spring 41 connected to the bar and to the bracket 1 which carries the pump.

When the forward end of the clutch controlling treadle is depressed by the operator to cause the machine to operate the rear end of the lever is raised and the arm 29 which is connected to the treadle is swung upwardly and the arm 31 extending from the hub of the arm 29 is swung downwardly. Upward movement of the arm 29 causes the lower end of the slot 25 in the upper end of the rod 23 to engage the pin 27 in the pump actuating arm 9 and to move the arm upwardly, which arm 9, when the machine is at rest, occupies a lowered position in engagement with a lug 43 on the bracket 1 on which it is pivoted,

in which position the arm is holding the pump plunger 12 down against the action of its spring, i. e., the spring referred to as 12 in U. S. Patent No. 2,051,250. The upward movement of the arm 9 allows the pump plunger to be raised by its spring in readiness to be moved down to force lubricant through the pipe 5 onto the needle 16 or needle guide. When the forward end of the treadle is depressed, the rocking shaft 6 is turned as described in U. S. Patent No. 2,056,670 and the roll 37 which engages the forward face of the bar 15 is thereby moved into a position which allows the bar 15 to be swung forwardly of the machine about its pivot 21 so that as the pump actuating arm 9 is moved upwardly the rear margin of the plate 13 on the arm 9 snaps over the shoulder 17 on the bar 15 and the pump actuating lever 9 is thereby held in its raised position temporarily even if the treadle is released. Also as the clutch controlling treadle is depressed, the spring 33 connecting the pump actuating arm and the arm 31 is further tensioned both by the downward movement of the arm 31 and the upward movement of the pump actuating arm 9.

During operation of the machine the pump actuating arm 9 is held in its raised position by the engagement of the plate 13 on the arm 9 with the shoulder 17 on the bar 15, and the slot 25 in the upper end of the rod 23, which is connected to the pump actuating arm, permits the clutch controlling treadle to be raised by the spring 33, which is connected to the pump actuating arm and to the arm 31, either to vary the speed of the machine or to stop the machine, the usual treadle raising spring of the machine being dispensed with.

The slot 25 in the upper end of the rod is sufficiently long to allow the treadle to be fully raised to stop the machine, and as the machine comes to rest the rocking shaft 6 is rotated in the manner described in U. S. Patent No. 2,056,670, and this movement of the rocking shaft causes the roll 37, supported thereby, to swing the bar 15 having near its upper end the shoulder 17, which is then supporting the pump actuating arm 9, rearwardly, thereby moving the shoulder 17 from beneath the plate 13 on the arm 9 and allowing the arm to be rapidly moved downwardly by the spring 33 connected to it to operate the pump plunger. The rapid downward movement of the pump actuating arm by its spring which is considerably stronger than the pump plunger spring causes lubricant to be squirted from the pipe onto that portion of the needle extending forwardly from the needle guide 34 or onto the needle guide itself or both onto the needle and the needle guide.

To enable lubricant squirted onto the top of the needle guide to readily flow therefrom onto the needle behind and in front of the guide, the needle guide of the machine may have a narrow opening formed in it which extends lengthwise of the needle guiding passage in the guide from one end to the other of the passage, the opening passing from the top face of the needle guide into the needle guiding passage. This opening is preferably additional to the usual opening which extends across the top of the guide.

The opening in the discharge end of the pipe 5 is comparatively small and the pipe is normally full of lubricant so that when the pump plunger is pressed down by the pump actuating arm, a small amount of lubricant is squirted out of the pipe. The amount of lubricant squirted out of the pipe may be varied by adjusting the screw 75

11 in the pump actuating arm 9 which engages the upper end of the pump plunger 12 and by its adjustment varies the amount of movement of the pump plunger after it commences to force 5 lubricant through the pipe and therefore controls the amount of lubricant expelled from the pipe.

The time in the last machine cycle before the machine comes to rest at which the lubricant is 10 squirted onto the needle may be varied, thus causing the lubricant to be applied to varying parts of the needle lengthwise thereof, by adjustment of the position of the roll 37 on the member which carries it by rotation of the eccentric pin 39 on which the roll is mounted and therefore adjustment of the time at which the 15 pump actuating arm is released by the shoulder on the bar.

The discharge end of the pipe through which 20 lubricant is conveyed to the needle is preferably arranged so that when the lubricant is squirted from the pipe the needle guide is in such a position that the lubricant is squirted onto the top of the front end of the needle guide and directly 25 onto the needle in front of the guide.

The illustrative embodiment may be used in a sewing machine having also a lubricating mechanism of the kind described in U. S. Patent No. 2,051,250 in which case the lubricant applied to 30 the needle by the illustrative embodiment supplements that applied by the latter mechanism and by its sudden squirting action ensures that the lubricant is applied to the needle at the desired time in the last cycle of the machine.

35 The nature and scope of the invention having been indicated, and a construction embodying the several features of the invention having been specifically described, what is claimed is:

1. In a sewing machine, the combination with 40 a needle, of a needle lubricating mechanism comprising a reservoir for lubricating fluid, a lubricating fluid conduit extending from the reservoir to a point in the vicinity of the needle, and means for squirting lubricant from the conduit 45 directly onto the needle.

2. In a sewing machine, the combination with a needle, of a needle lubricating mechanism comprising a reservoir for lubricating fluid, a lubricating fluid conduit extending from the reservoir 50 to a point in the vicinity of the needle, and means for squirting lubricant from the conduit onto a predetermined portion of the needle lengthwise thereof and during movement of the same.

55 3. In a sewing machine, the combination with a needle, of a needle lubricating mechanism comprising a reservoir for lubricating fluid, a lubricating fluid conduit extending from the reservoir to a point in the vicinity of the needle, and means

operating upon stopping the machine and before the machine comes to rest for squirting lubricating fluid from the conduit onto the needle subsequent to the withdrawal of the needle from the work.

4. In a sewing machine, the combination with a needle, of a needle lubricating mechanism comprising a reservoir for lubricating fluid, a lubricating fluid conduit extending from the reservoir to a point in the vicinity of the needle, means 10 actuated upon stopping the machine for squirting lubricant onto the needle during the last cycle of the machine and subsequent to the withdrawal of the needle from the work, and means for varying the time in the last cycle of the machine at which 15 the lubricant is squirted onto the needle, whereby the lubricant may be applied to varying portions of the needle length thereof.

5. In a sewing machine, the combination with a needle, of a needle lubricating mechanism 20 comprising a reservoir for lubricating fluid, a conduit for conducting lubricant from the reservoir to a point in the vicinity of the needle, means comprising a plunger for forcing lubricant through the conduit, means operating upon stopping the machine to actuate the plunger suddenly, whereby lubricant is forced through the conduit and squirted from the end of the same onto the needle during the last cycle of the machine and subsequent to the withdrawal of the 30 needle from the work, and means for varying the amount of lubricating fluid squirted from the conduit.

6. In a sewing machine, the combination with a needle, of a needle lubricating mechanism comprising a reservoir for lubricating fluid, a lubricating fluid conduit extending from the reservoir to a point in the vicinity of the needle, a plunger for forcing lubricant through the conduit, and means for actuating said plunger including a 35 member adapted to be tensioned upon starting the machine and retained in tensioned condition during the continued operation thereof, and to be released upon stopping the machine to cause the plunger suddenly to be actuated, whereby lubricant is forced through the conduit and squirted 40 therefrom onto the needle subsequent to its withdrawal from the work.

7. In a sewing machine, the combination with a needle, of mechanism for applying liquid to the 50 needle at the end of the sewing operation to prevent particles of material from sticking and drying thereon while the machine is at rest, said mechanism comprising a reservoir for the liquid, a liquid conduit extending from the reservoir to a point adjacent the needle, and means for squirting the liquid directly onto the needle at the end of the sewing operation.

HAROLD ERNEST ELLIOTT.

CERTIFICATE OF CORRECTION.

Patent No. 2,170,554.

August 22, 1939.

HAROLD ERNEST ELLIOTT.

It is hereby certified that error appears in the printed specification of the above numbered patent requiring correction as follows: Page 3, second column, line 18, claim 4, for the word "length" read lengthwise; and that the said Letters Patent should be read with this correction therein that the same may conform to the record of the case in the Patent Office.

Signed and sealed this 31st day of October, A. D. 1939.

(Seal)

Henry Van Arsdale,
Acting Commissioner of Patents.
